LAP TABLE

Filed July 26, 1951

FIG. 1

A technical diagram of a rectangular frame, likely made of metal, with a dashed line indicating its outer boundary. The frame features several components: a circular hole at the top left labeled 5; a small rectangular cutout with a hinge at the top center labeled 4; a wavy horizontal strip labeled 16; a vertical strip labeled 18; and a vertical strip labeled 2. On the right side, there is a vertical strip labeled 17, a small rectangular cutout with a hinge labeled 15, and a vertical strip labeled 13. The bottom edge of the frame is labeled 8 on the left and 6 on the right. The corners of the frame are rounded.

LAP TABLE

George B. Bodenhoff, Cleveland, Ohio, assignor
to Anthony M. Golubich, Cleveland, Ohio

Application July 26, 1951, Serial No. 238,741

2 Claims. (Cl. 311—25)

1

This invention relates, as indicated, to lap tables or trays, but has reference more particularly to a device of this character which has been especially designed for use in the home or by salesmen and others while traveling.

A primary object of the invention is to provide a device of the character described, which is contoured to fit the body and thighs or lap of the user.

Another object of the invention is to provide a device of the character described having a novel supporting leg or member which is foldable to an operative and inoperative position.

A further object of the invention is to provide a device of the character described, having a novel form of hinge connection and stop element, whereby the supporting leg or member may be easily removed or assembled with the table, and effectively supported in upright or open position.

Other objects and advantages of my invention will be apparent during the course of the following description. In the accompany drawings forming a part of this specification and in which like numerals are employed to designate like parts throughout the same,

Fig. 1 is a top plan view of a tray, embodying a preferred form of the invention;

Fig. 2 is a bottom plan view of the tray, with the tray supported member in collapsed or closed condition;

Fig. 3 is a side or end elevational view of the tray;

Fig. 4 is a fragmentary portion of Fig. 2, on an enlarged scale;

Fig. 5 is a fragmentary cross-sectional view, taken on the line 5—5 of Fig. 4;

Fig. 6 is a fragmentary cross-sectional view, taken on the line 6—6 of Fig. 4;

Fig. 7 is a view similar to Fig. 4, but showing a modification;

Fig. 8 is a fragmentary cross-sectional view, taken on the line 8—8 of Fig. 7, and

Fig. 9 is a fragmentary cross-sectional view, taken on the line 9—9 of Fig. 7.

Referring more particularly to Figs. 1 to 6 inclusive of the drawings, the lap table or tray will be seen to comprise a table or tray, generally designated by reference numeral 1, and a supporting leg or member, generally designated by reference numeral 2.

The table 1 is preferably molded in one piece, from a plastic, such for example, as Styron, and has a generally flat upper and lower surface, the upper surface having a peripheral upstanding flange 3, which extends entirely around the table,

2

and serves to confine objects on the table and prevent them from falling or being pushed off the table. The table also has a recess 4 therein, adjacent the upper edge thereof, which recess is adapted to receive and hold a pencil, pen or the like, and also has a depending, closed-bottom, hollow protuberance 5, for the reception of a glass tumbler, a bottle of ink, paper fasteners or clips, or other objects.

10 The table is further formed to provide a longitudinal recess 6 in its lower edge, which is contoured to receive a portion of the abdomen of the user of the tray, so as to enable the tray to more closely conform to the body of the user, as well as to provide ends 7 and 8, which function to prevent lateral displacement of the tray while in use on a person's lap.

Molded integrally with and extending from the rear or lower surface of the table 1 is a pair of spaced bearings 9 and 10 having openings 11 of substantially circular cross-section extending therethrough.

Also molded integrally with and extending from the rear or lower surface of the table 1, is 25 a pair of spaced stop elements or abutments 12 and 13, the element 12 extending laterally from the bearing 9 and in a radially inboard direction, being provided with an inclined surface 14, and the element 13 extending laterally from the bearing 10 and in a radially inboard direction, being provided with an inclined surface 15, coplanar with the surface 14 of the element 12.

The supporting member or leg 2 is preferably formed from a single piece or length of wire, of 35 fairly heavy gauge, and is bent to provide spaced arcuate portions 16 and 17, which are designed to fit and conform to the thighs of the user, when the tray is in operative position, that is to say, when the member 2 is in open or unfolded position.

40 The member 2 is also formed to provide spaced parallel arms 18 and 19, at the ends thereof, which terminate in radially-outwardly extending trunnion elements 20, which are disposed in the openings 11 of the bearings 9 and 10, so as to permit pivotal movement of the member 2 in said bearings.

The member 2 may be folded flat against the rear surface of the tray 1, as shown in broken lines in Fig. 3, in which position the tray and supporting member form a compact, flat, unit, which facilitates storage and shipment thereof.

When it is desired to use the tray, the member 2 is unfolded or opened to the solid line position shown in Fig. 3, in which position, the arms 18

and 19 come into abutment with the surfaces 14 and 15 respectively, which thereby prevent movement of the member 2 beyond this position. With the member 2 thus positioned, the tray is placed on the lap of the user, with the recess 6 adjacent the abdomen of the user and the portions 16 and 17 disposed on the thighs or legs of the user. In this manner, the table is comfortably supported, and can be used for eating, writing, etc., without fear of displacement from the lap of the user.

It is thus seen that I have provided a lap table which is admirably adapted for use in the home and on the road, which is contoured to fit the body and thighs of the user, and which is characterized by a novel supporting leg or member, foldable to operative and inoperative positions, and a novel hinge connection and stop element, whereby the supporting leg or member may be easily removed or assembled with the table, and effectively supported in upright or open position. The supporting leg may be easily removed by springing the arms 18 and 19 inwardly to remove the trunnions 20 from the openings 11. This springing of the arms 18 and 19 is facilitated by reason of the contour of the supporting member.

In that form of the invention shown in Figs. 7, 8 and 9, the table 1' is preferably formed of heavy cardboard or the like, having any desired surface finish or covering, such as a wood-simulating paper.

Secured to the table 1', as by means of hollow rivets 21, is a pair of laterally-spaced hinge elements 9', which are located in approximately the same position at the back or bottom of the table 1', as the elements 9 and 10 with respect to the table 1.

The elements 9' are preferably stamped from sheet metal and are bent intermediate their ends to provide bearing portions 11' of substantially circular cross-section which receive the trunnion elements 20 of the supporting member 2.

Each of the elements 9' is provided with a portion 12' which extends in an inboard direction from the element 9', is formed integrally with the latter, and is provided with an upwardly

curved portion 14', which serves the same function as the surfaces 14 and 15 of the previously described form of the invention, that is to say, the arms 18 and 19 of the member 2 come into abutment with these portions 14' which thereby prevent movement of the member 2 beyond this position.

It is to be understood that the forms of my invention, herewith shown and described, are to be taken as preferred examples of the same, and that various changes in the shape, size and arrangement of parts may be resorted to, without departing from the spirit of my invention, or the scope of the subjoined claims.

Having thus described my invention, I claim:

15 1. In a lap table of the character described, a substantially flat table having laterally-spaced bearing elements extending from the bottom of said table, a table supporting member formed from a single length of wire comprising parallel-spaced arms and having trunnions on their ends disposed in said bearing elements, said bearing elements having portions extending laterally therefrom and formed integrally therewith and lying in the path of movement of said parallel arms to arrest movement of said supporting member, whereby said supporting member is pivotally movable from a position substantially parallel with said table to an operative position more than 90 degrees from said first-named position.

20 2. A lap table as defined in claim 1, in which said bearing elements are formed from sheet metal, and are riveted to said table, said laterally extending portions of said bearing elements being formed integrally with the bearing elements.

GEORGE B. BODENHOFF.
